UNITED STATES PATENT OFFICE.

GEORGE RUEL CROSS, OF LEWISTON, MAINE.

CHIMNEY-CAP.

SPECIFICATION forming part of Letters Patent No. 740,247, dated September 29, 1903.

Application filed May 27, 1903. Serial No. 158,955. (No model.)

To all whom it may concern:

Be it known that I, GEORGE RUEL CROSS, a citizen of the United States, and a resident of Lewiston, in the county of Androscoggin and 5 State of Maine, have invented a new and Improved Chimney-Cap, of which the following is a full, clear, and exact description.

This invention relates to caps for draft-stacks or chimneys built of stone or bricks, 10 and has for its object to provide a chimney-cap of novel construction mainly formed of cement, thus providing a shapely, inexpensive, and durable cap-piece as a finish for chimneys of the character specified.

15 The invention consists in the novel construction and combination of parts, as is hereinafter described, and defined in the appended claims.

Reference is to be had to the accompanying 20 drawings, forming a part of this specification, in which similar characters of reference indicate corresponding parts in all the figures.

Figure 1 is a perspective view of the improved chimney-cap in position upon the top 25 of a chimney. Fig. 2 is a transverse sectional view of the cap and chimney, substantially on the line 2 2 in Fig. 1. Fig. 3 is a partly-sectional reversed plan view of the chimney-cap. Fig. 4 is a perspective view of a modified form of the improvement, and Fig. 5 is a partly-sectional reversed plan view of the modified form of the chimney-cap shown in 30 Fig. 4.

The improvement is intended for application 35 upon chimneys of any dimensions or area in plan of the upper end surface and is particularly well adapted for the completing bonnet or cap on draft-flues or chimneys in buildings, and it may be of rectangular or of some 40 other polygonal form.

In the drawings that represent the construction and application of the improved cap, A represents the top portion of a brick chimney having a straight vertical flue *a* therein, said 45 chimney top and flue having rectangular contours that are parallel between respective sides of the same. The chimney-cap when formed to surmount a chimney A having the 50 central vertical flue *a* therein—that is, to continue through the cap—is constructed, essentially, as shown in Figs. 1, 2, and 3, comprising the following details:

In a suitable matrix (not shown) the centrally-apertured cap-block 10 is formed of cement in plastic condition, the cement material being thus shaped to give it rectangular peripheral form and produce the aperture *a'* therein at the center having a corresponding contour. The sides of the rectangular aperture *a'* are disposed parallel with respectively opposite exterior sides of the cap-block, and, as shown in Figs. 1 and 2, the upper surface of the cap-block is sloped downward and outward from each edge of the aperture *a'* to a corresponding outer edge of the cap-block, 65 thus adapting it to shed rain or snow. In the lower side of the cap-block 10 a flat-bottomed rectangular recess *b* is formed, having proper area to adapt the cap-block to seat upon the level upper surface of the chimney 70 A. The formation of the recess *b* affords two rectangular depending flanges *c* *c'*, respectively, at the inner and outer edges of the recess *b*, these flanges embracing the inner and outer edges of the upper end of the chimney, as is clearly shown in Fig. 2. To give 75 strength and endurance to the cement body of the cap-block 10, it is reinforced by the embedment therein of a tessellated frame, preferably formed of strips of metal, that is 80 rendered non-oxidizing by galvanizing it or coating the same with a suitable paint. As shown, the plurality of metal strips 11 are formed into any preferred number of rectangular rings that are graded in size and so 85 proportioned in relative diameter that when placed one within the other in regular order a suitable space will be provided between them. The several frame-rings are held spaced apart by the spacing bars or strips 90 11^a, which unite the rings and hold them separated to produce a skeleton or tessellated frame.

It will be seen that the embedment of the reinforcing-frame within the plastic material 95 of the cap-block 10 while it is receiving form will render it quite strong and adapt the cap-block to sustain considerable breaking strain without permanent injury, as the block if cracked by rough usage will not fall into 100 pieces, being held by the metal frame from fragmentary separation, so that the crevices may be filled and the block be rendered solid again by the introduction of liquid cement

into the cracks, which when "set" will re-unite all parts of the cap-block.

In the construction of chimneys for certain situations it is found that to enable the chimney to have proper "draft" it is advantageous to provide a non-perforate cap-block therefor, which will seal the top of the chimney. In this construction of the cap-block, that is shown at 10^a in Figs. 4 and 5, there are one or more lateral openings A' formed in the chimney A at or near its upper end. If the lateral openings A' are in the form of recesses in the upper surface of the chimney and the lower surface of the cap-block 10^a forms the upper surface of such opposite openings, there will remain two piers A², that form the side walls of the openings. In this case there may be two depending rectangular border-flanges e e, formed on the lower side of the cap-block 10^a, which are designed to respectively embrace the upper edges of the chimney-piers A², and thus bind the cap-block on the upper end of the chimney. When the cap-block is formed without a central opening in it, the tessellated frame that is composed of a series of rings that are held spaced apart, as before explained, may extend across the central portion of the cap-block, and thus bind all portions of the same together, as is indicated by dotted lines in Fig. 5.

In mounting the cap-block 10 or 10^a upon a chimney there is a thin coating of cement mortar first applied upon the upper flat surface of the chimney, which will have intimate contact with the lower surface of the

cap-block when it is seated thereon, and will practically unite the cap-block with the chimney.

When in position, the cap-block adds a neat finish to the chimney, renders its top very durable, and obviously protects adjacent portions of the chimney-wall, and in case the chimney is painted to finish it in harmony with the building it surmounts the cap-block may also be similarly painted with a waterproof paint of proper color.

Having thus described my invention, I claim as new and desire to secure by Letters Patent—

1. A chimney-cap, comprising a rectangular cement body having a central aperture, and depending flanges respectively projecting from the wall of the aperture, and the exterior wall of the cap, and an interior reinforcing-frame formed of metal strips bent into rectangular ring form, and held spaced apart by strips of metal joined by their ends upon respective rings.

2. A chimney-cap comprising a rectangular cement body having a central aperture, depending concentric flanges thereon, and an interior tessellated reinforcing-frame surrounding the aperture.

In testimony whereof I have signed my name to this specification in the presence of two subscribing witnesses.

GEORGE RUEL CROSS.
